UNITED STATES PATENT OFFICE.

ALEC J. GERRARD AND PARVIN WRIGHT, OF CHICAGO, ILLINOIS.

WIRE DEFORMING AND SEVERING MACHINE.

Application filed November 29, 1920. Serial No. 427,102.

To all whom it may concern:

Be it known that we, ALEC J. GERRARD and PARVIN WRIGHT, respectively, a subject of the King of Great Britain, and a citizen 5 of the United States, each residing at Chicago, in the county of Cook and State of Illinois, have invented certain new and useful Improvements in Wire Deforming and Severing Machines; and we do hereby 10 declare the following to be a full, clear, and exact description of the invention, such as will enable others skilled in the art to which it appertains to make and use the same.

This invention relates to wire straightening and deforming machines, and has for its 15 object to provide a mechanism of this nature which will be simple in construction, comparatively inexpensive to manufacture, and more efficient in use than those which 20 have been heretofore proposed.

With these and other objects in view the invention consists in the novel details of construction and combinations of parts more 25 fully hereinafter disclosed and particularly pointed out in the claims.

In order that the precise invention may be the more clearly understood it is said:—Machines which require straightened lengths of wire with which to band packages are well 30 known. These machines usually secure one end of the straightened wire in a slotted post, while the bight of the wire is passed around the package and returned back to and beyond said post prior to the tensioning and 35 wire twisting or tying operation.

Machines of this character having wire holding posts whose slots are of a less width than are the diameters of the wires to be used therein are also now known. In these last 40 named machines, invented by us, the wire is deformed, or flattened, near its extreme end leaving a shoulder at each end of the flattened portion, so that said flattened portion may readily enter the said last named slot, 45 and the wire be held by the shoulder at the outer end thereof.

The flattening of wire ends are not only troublesome, but should the operator take hold of the wrong end of the wire he is put 50 to the annoyance of turning it end for end, which takes time and lowers the efficiency of the machine.

The purpose of this invention more specifically stated is to provide a means for automatically flattening both ends of the

straightened lengths of wire, and to flatten to the same degree wires of different sizes so that they may all be used in the same machine without having to change the wire holding post. 60

A further object of the invention is to provide the trade with straightened lengths of wire differing in size, and having each end flattened or deformed to a uniform cross-section, all as will hereinafter appear. 65

Referring to the accompanying drawings forming a part of this specification in which like numerals designate like parts in all the views:—

Figure 1 is a side elevational view of a 70 straightening and deforming machine made in accordance with this invention;

Figure 2 is a plan view partially in section of a portion of the parts shown in Figure 1; 75

Figure 3 is a sectional view taken on the line 3—3 of Figure 2;

Figure 4 is a diagrammatic view illustrating the deformed and severed wire;

Figure 5 is a sectional view taken on the line 5—5 of Figure 2;

Figure 6 is a sectional view taken on the line 6—6 of Figure 2;

Figure 7 is a sectional view taken on the line 7—7 of Figure 1; 85

Figure 8 is an end elevational view partially in section of the extreme right hand end of the machine as seen in Figure 1; and

Figure 9 is a view of a wire holding post adapted to receive deformed wires of different sizes. 90

1 indicates any suitable frame work on which is mounted a power pulley 2, having a shaft 3 carrying a driving friction disk 4, engaging the driven disk adapted to rotate 95 the change gears 6 and 7, all as will be clear from Figures 1, 2 and 6.

Surrounding the power shaft 3 is a sleeve 8 capable of being connected to and disconnected from said pulley 2 by the clutch 9 100 operated by the arm 10, carried by the rod 11 having the arm 12 rotated by pin 13 on the gear 14 meshing with the pinion 15 mounted on the shaft 3 and continuously rotating with said friction disk 4, all as will be 105 clear from Figure 2. Mounted on said sleeve 8 and rotating therewith is the cam 16 on which rides the roller 17, mounted on the bracket 18, rigid with the housing 19, in which the change gears 6 and 7 are mounted. 110

As is best shown in Figure 5, said housing 19 together with said change gears 6 and 7 can be raised around the shaft 20 as a center when the cam 16 lifts said housing by reason of its contact with the roller 17.

It will now be clear that as the pulley 2 and shaft 3 continuously revolve, the sleeve 8 will be intermittently driven from said pulley and the cam 16 will intermittently raise and lower said housing 19 on its pivot 30 and thus disconnect and connect at predetermined intervals the friction disk 5 with the continuously rotating driving disk 4. It will further be clear that during said connection the driven disk 5 will rotate the change gears 6 and 7 and the shaft 20, while said parts will be idle during the periods of disconnection.

The wire 21 to be cut into lengths and whose ends are to be deformed, is unwound from a reel not shown, is then lead between the two sets of straightening rolls 22 and 23, disposed at right angles to each other, and is then lead over the wire driving disk 24 mounted on the shaft 20 which intermittently drives or feeds said wire forward a distance depending upon the speed of rotation of said shaft 20 which is governed by the speed changing gears 6 and 7 as will be readily understood. In order to make positive the feed of the wire 21 the disk 24 is grooved as best shown in Figure 6, and a correspondingly shaped disk 26 mounted on shaft 27 rotated by the gears 28 mesh with the gears 7, fits said groove and forcibly moves said wire forward whenever said gears 7 are rotated. Said gears 7 and 28 are only very loosely meshed together as illustrated in Figure 5, so that the screws 30 may adjust the shaft 27 up and down to cause the disk 26 to grip wires of different gages. Also mounted on the sleeve 8 is a pair of cams 31 and 32 respectively operating the rollers 33 and 34 carried by the arms 35 and 36 respectively pivoted as at 37 and 38 as shown.

The lever 35 carries the wire deforming and cutting jaw 40 while the lever 36 carries the similar jaw 41. That is to say, as will be clear from Figures 2 and 4, the jaws 40 and 41 are provided with deforming dies 43 each provided with deforming members 45 and cutting members 46, so that when a predetermined length of wire is forcibly fed between said jaws and stopped by reason of the disks 4 and 5, having been disengaged said jaws 40 and 41 will be brought together by the cams 31 and 32 with the result that the wire 21 will not only be deformed but will also be cut in two as indicated in Figure 4.

Before the wire deforming operation just described takes place, the extreme right hand end of the wire as seen in Figures 1 and 2 will have passed to the left hand end of the fluted revolving drum 50 provided with

the gear 51 meshing with the toothed wheel 52 mounted on the shaft 53 carrying the star wheel 54 operated by the lug 55 carried by the sleeve 8. It thus results that as the wire 21 is forced forward by the feed rolls 24 and 28 it occupies one of the grooves in the drum 50, and when it is severed by the means disclosed the pin 55 will turn the wheel 54, shaft 53, wheel 52, and drum 50, so that said severed wire after having fallen into the trough 58 underlying said drum 50 is swept out of the same by one of the fluted members of said drum, and is caught on the curved arms 59 mounted on the shaft 60 carried by the frame 61 supporting said drum 50. At the end of the drum 50 is a counting device 62 provided with a pin 70, see Figure 8, taking against a lever 71 pivoted at 72 having a dog 73 taking in a slot 74 carried by a disk 75 mounted on the shaft 60, and thus preventing said shaft and arms 59 from turning.

When a predetermined number, say 250, of said severed and straightened lengths of wire have, however, fallen onto said arms 59, the pin 70 will lift the dog 72 and permit the weight of the bundle of wires to turn said arms 59 and shaft 60 so that the bundle will roll out onto the cradle 64 ready to be prepared for shipment.

The operation of this machine will be clear from the foregoing but may be briefly summarized as follows:—

Power being applied to the pulley 2, the shaft 3 is continuously rotated which imparts motion to the friction disks 4 and 5, to the change gears 6 and 7, the shaft 20 and the grooved wire feeding disk 24. Said power also imparts motion to the gears 28, shaft 27, and wire feeding disk 26, fitting the groove in the disk 24. When wires of different sizes are to be deformed in this machine, the screw mechanism 30 is adjusted so that the disks 26 and 24 will properly grip the wire whatever may be its size and thus insure that it is positively fed through the machine.

Mounted on the power shaft 3 is a sleeve 8 which through the cam 16 and roller 17 turns the change gear housing 19 together with the change gears and disk 5 on the shaft 20 as a center, and thus at each rotation of said sleeve 8, the friction disk 5 is disengaged from the friction disk 4 so that the feeding operation is stopped only to be started again when the cam 16 has disengaged the roller 17 and the disk 5 has re-engaged the disk 4.

This said sleeve 8 receives its motion from shaft 3, by reason of a pinion 15 mounted thereon engaging the gear 14 provided with the pin 13 coacting with the arm 12, shaft 11, and arm 10 to intermittently engage the clutch member 9 with the hub of the power pulley 2.

That is to say, it will require a plurality of revolutions of the power shaft 3 to produce one revolution of the sleeve 8, and thus will there occur a plurality of revolutions of the feeding disks 24 and 26 to each revolution of the power shaft 3. It is evident that by changing the speed of the shaft 20, by suitably manipulating the change speed gears 6 and 7, the speed with which the wire is fed will also be changed, and therefore, with a steady rotation of the pulley 2, different lengths of wire 21 may be fed forward by the disks 24 and 26 at will. The said wire 21 is thus positively fed forward into one of the flutes of the drum 50, and above the holding tray or member 58, until the feeding means is thus stopped. In this manner is a predetermined length of wire automatically fed into the tray 58 whereupon the feed being stopped it is automatically deformed and severed in a manner now to be disclosed. That is to say, the rotation of the sleeve 8 causes the cams 31 and 32 to bring the deforming dies 45 against a bight of the wire, thus forming flat depressions 80 therein, having the abrupt shoulders 81 at the ends of said depressions and simultaneously with this deforming action is the said bight of the wire severed midway between said depressions as indicated at 82, Figure 4.

It thus results that one end of the severed length of the wire is deformed in the manner disclosed while the other end of the oncoming wire is likewise deformed with the result that when the bight of the oncoming wire is severed the finished length of wire will have both ends deformed as is best illustrated in Figure 4. It will therefore be clear that when one uses a length of wire deformed at both ends in a manner disclosed, he will not be subjected to the annoyance of getting hold of an undeformed end and attempting to put it into a slotted post such as 85 which will not receive it.

In addition to this, it is evident that should one owning a wire tying machine purchase wires 21, 210, see Fig. 9, of different sizes he will not be subjected to the annoyance of finding that the flattened cross sections 80 of his different sized wires are unsuited to the slot 86 in his post 85 with which his machine is provided, for owing to the throw of the deforming members 45 being uniform no matter what may be the size, of the wire being deformed, the cross sections 80 will always be uniform. The lengths of wire 21 after having been thus severed and deformed, will fall upon the tray 58, see Figure 7, whereupon they will be swept by the flutes of the drum 50 out of said tray and caught upon the curved arms 59.

Owing to the action of the counting mechanism 62, best illustrated in Figure 8, after

a predetermined number of wires have thus been caught on curved arms 59 the dog 73 will lift, thus releasing said arms 69 and permitting the bundle of straightened and deformed wires to fall by gravity into the curved arms or rack 64, whence they may be taken and packaged ready for shipment.

It will now be seen that wires such as 21 of various sizes may be readily drawn through the straightening rollers 22 and 23 75 from a coil not shown, so that all tendency to kink or twist is taken out of said wires, that the wires are rapidly forced with certainty for a predetermined distance into the flutes of the drum 50 so that they are automatically measured as to length whereupon they are rapidly deformed and severed into predetermined lengths. It will further be clear that should it be desired to have the lengths of the severed wires changed, it is 80 only necessary to change the speed of the shafts 20 and 27 which is readily effected by manipulating the change speed gears 6 and 7 in the manner well known.

Of course, instead of making the deformed portion 80 flat in cross section it may be made round in cross section or it may have any other desired cross sectional shape.

It is obvious that those skilled in the art may vary the details of construction as well 95 as the arrangement of parts without departing from the spirit of our invention, and therefore, we do not wish to be limited to the above disclosure except as may be required by the claims.

What we claim is:—

1. In a machine for deforming the ends of wires, the combination of means for feeding the wire through the deforming mechanism; a rotating means provided with a 105 groove for receiving the fed wire; means for supporting the fed wire; means for stopping the feeding means; means for deforming the fed wire; and means for severing the deformed wire, substantially as described.

2. In a machine for deforming the ends of wires, the combination of automatic means for feeding the wire through the deforming mechanism; a rotating means provided with a groove for receiving the fed wire; means 115 for supporting the fed wire; automatic means for stopping the feeding means; automatic means for deforming the fed wire; and automatic means for severing the deformed wire, substantially as described.

3. In a machine for deforming the ends of wires, the combination of means for straightening the wire to be deformed; means for feeding the straightened wire through the deforming mechanism; a rotating means provided with a groove for receiving the fed wire; means for supporting the fed wire; means for stopping the feeding means after a predetermined length of wire has passed said deforming mechanism; 125

means for deforming the fed wire; and means for severing the deformed wire substantially as described.

4. In a machine for deforming wires the combination of means for straightening the wire to be deformed; means for moving said wire through a predetermined distance; a rotating means provided with a groove for receiving the fed wire; means for supporting the fed wire; means for deforming the wire at one end of said distance; and means for severing said wire during the deforming operation, substantially as described.

5. In a machine for deforming wires the combination of automatic means for straightening the wire to be deformed; automatic means for moving said wire through a predetermined distance; a rotating means provided with a groove for receiving the fed wire; means for supporting the fed wire; automatic means for stopping the movement of said wire after it has moved through said distance; means for deforming the wire at one end of said distance; and means for severing said wire during the deforming operation, substantially as described.

6. In a machine for deforming wires the combination of a continuously rotating source of power; means for positively feeding a wire operated from said source; means for automatically stopping and starting the feeding action; a rotating means provided with a groove for receiving the fed wire; means for supporting the fed wire; and means for deforming and severing said wire between the said stopping and starting operations, substantially as described.

7. In a machine for deforming wires the combination of a continuously rotating source of power; means for straightening the wire to be deformed; means for positively feeding a wire operated from said source; means for readily changing the speed of the feeding means; a rotating means provided with a groove for receiving the fed wire; means for supporting the fed wire; means for automatically stopping and starting the feeding action; and means for deforming and severing a bight of said wire between the said stopping and starting operations, substantially as described.

8. In a machine for deforming wires the combination of a continuously rotating shaft; a change gear mechanism operated by said shaft; means for positively feeding wires operated from said change gear mechanism; a rotating means provided with a groove for receiving the fed wire; means for supporting the fed wire; intermittently operated means for stopping the operation of said change gear mechanism; intermittently operating wire deforming and cutting

means acting after the stopping of said change gear mechanism; and means to remove the deformed and severed wire from the machine, substantially as described.

9. In a machine for deforming wires the combination of a continuously rotating shaft; a change gear mechanism operated from said shaft; means for positively feeding wires operated from said change gear mechanism; a rotating means provided with a groove for receiving the fed wire; means for supporting the fed wire; intermittently operated means comprising a cam for stopping the operation of said change gear mechanism; intermittently operating wire deforming and cutting means comprising a pair of rotating cams acting after the stopping of said change gear mechanism; and means comprising a rotating fluted drum to remove the deformed and severed wire from the machine, substantially as described.

10. In a machine for deforming wires, the combination of means for straightening the wire to be deformed; means for positively feeding the straightened wire through a predetermined distance; a rotating means provided with a groove for receiving the fed wire; means for supporting the fed wire; means to stop the wire after said distance has been reached; means to deform a bight of the wire after it has been stopped; means to sever said bight during the deforming operation; means to remove the deformed severed wire from the machine, substantially as described.

11. In a machine for deforming wires, the combination of means for straightening the wire to be deformed; means to positively feed the straightened wire through a predetermined distance; means to adjust the feeding means for different sizes of wire; a rotating means provided with a groove for receiving the fed wire; means for supporting the fed wire; means to stop the wire after said distance has been reached; means to deform a bight of the wire after it has been stopped; means to sever said bight during the deforming operation; and means comprising a fluted drum to remove the deformed severed wire from the machine, substantially as described.

12. In a wire deforming machine the combination of means to positively feed wires of varying sizes; a rotating means provided with a groove for receiving the fed wire; means for supporting the fed wire; means to deform said varying sized wires to a uniform cross section; and means to sever the deformed wires, substantially as described.

In testimony whereof we affix or signatures.

ALEC J. GERRARD,
PARVIN WRIGHT.
